Primary Examiner — Rashida C. Walshon(74) *Attorney, Agent, or Firm* — SHERMAN IP LLP; Kenneth L. Sherman; Steven Laut(57) **CLAIM**

The ornamental design for a lacing device for boxing gloves, substantially as shown and described.

DESCRIPTION

FIG. 1 is a rear view of a lacing device for boxing gloves showing my new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and,

FIG. 8 is another perspective view of the lacing device for boxing gloves.

Shading and stippling in FIGS. 1-8 represent materials from which the strap material is constructed and form no part of the claimed design. Features shown in broken lines form no part of the claimed design.
